Des. 234,873
Patented Apr. 15, 1975

234,873

FUEL DISPENSER FOR SERVICE STATIONS

Richard H. Wheeler, Fort Wayne, Ind., assignor to
Tokheim Corporation, Fort Wayne, Ind.

Filed May 17, 1973, Ser. No. 361,301

Term of patent 14 years

Int. Cl. D20—02

U.S. Cl. D52—2 A

The figure is a perspective view of a fuel dispenser for service stations showing my new design, the opposite sides not shown are substantially identical to those shown.

I claim:

The ornamental design for a fuel dispenser for service stations, substantially as shown and described.
